UNITED STATES PATENT OFFICE.

MOSES B. DISKIN, OF NEW YORK, N. Y.

BOX FORM OR MANDREL.

Application filed April 28, 1922. Serial No. 557,148.

To all whom it may concern:

Be it known that I, MOSES B. DISKIN, a citizen of the United States, residing at New York city, in the county of New York and State of New York, have invented certain new and useful Improvements in Box Forms or Mandrels; and I do hereby declare the following to be a full, clear, and exact description of the invention, such as 10 will enable others skilled in the art to which it appertains to make and use the same.

The present invention relates to forms or mandrels used in the manufacture of paper boxes, and the like, and aims to provide a 15 novel and improved adjustable form or mandrel.

Another object of the invention is the provision of a box form or mandrel of novel and improved construction capable of adjustment whereby the device can be used for the making of boxes of different sizes of the same shape.

A further object is the provision of novel means for adjustably mounting the members 20 which define the shape of the box, whereby they can be positioned for making boxes of different sizes.

A still further object is the provision of a novel and improved adjustable bottom support for the box bottom, which is adjustable to correspond to the adjustment of the members which define and support the walls 30 of the box.

It is also an object of the invention to 35 provide such an improved box form or mandrel which is comparatively simple and inexpensive in construction, which can be applied to various box making machines, which provides for the making of box forms 40 in different shapes, and which is practical and efficient in use.

With the foregoing and other objects in view, which will be apparent as the description proceeds, the invention resides in 45 the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a plan view of the improved box form, portions being broken away.

Fig. 2 is a section on the line 2—2 of Fig. 1.

Figs. 3, 4 and 5 are fragmentary plan views showing box forms or mandrels of different shapes.

A central tubular member 10 is provided 60 for supporting the other parts of the form, and is adapted to be fitted on the terminal of a shaft 11 of a box making machine, said supporting member 10 carrying a set screw 12 to enter an annular groove 13 in said 65 shaft for retaining the form in place and permitting the form and shaft to be rotated relatively to one another.

The form or mandrel is of skeleton construction, and the sides or walls of the box 70 are defined by the side bars 14 parallel with the central supporting member 10, and said bars 14, as shown in Figs. 1 and 2, provide the outline of a rectangular box, and the paper is wound on the form around the bars 75 14 to give the box its shape. Each bar 14 is supported by a pair of crossed links 15 and 16, pivoted together at their point of crossing, as at 17. The links 15 are pivoted to the bars 14, as at 18, while the links 16 have 80 studs or pins 19 engaging slidably in longitudinal slots 20 in said bars, to provide for the adjustment of the bars 14 toward and away from the member 10 when the links 85 are swung relatively to one another, keeping the bars 14 parallel with said member 10. The inner ends of the links are pivotally connected with plates 21 and 22 mounted on the member 10, and these plates are of the 90 shape of the box to be formed, only smaller. The plate 21 is secured in place on the member 10 by means of a set screw 23, while the plate 22 is adjustable toward and away from the plate 21 in order to obtain the adjustment of the bars 14.

As shown, the plates 21 and 22 have slots 24 in the edge portions thereof receiving the inner ends of the links 15 and 16, and said links have pivot studs or pins 25 seated in notches between the edge portions of the 100 plates and retaining members 26 secured to said plates by means of bolts 27 or the like. The studs or pins 25 are thus pivotally anchored between the plates and retaining members, providing a convenient manner of 105 pivotally assembling the links with said plates.

The adjusting means of the plate 22, as shown, includes a nut 28 screw-threaded on the member 10 and having a socket portion 110 29 receiving a boss 30 of the plate 22, said boss having an annular groove 31 receiv-

ing a screw 32 carried by the socket portion 29, whereby the plate 22 is connected with the nut by a swivel joint, permitting the nut to be rotated for moving the plate 22 longitudinally on the member 10.

By adjusting the plate 22 away from the plate 21, the links are made to swing toward the axis of the form, thereby moving the bars 14 toward the member 10, and reducing the size of the form, and, vice versa, when the plate 22 is adjusted toward the plate 21, the bars 14 are moved away from the member 10 to increase the size of the form, the shape of the form remaining the same in the several adjustments. In this way, the form can be adjusted for making boxes of different sizes having the same shape. This provides for the convenient adjustment of the form or mandrel for the production of boxes of different sizes having the same shape and relative proportions, without using a different size of form for each size of box wanted. The box is made in the customary manner, by wrapping or winding the paper around the form, as well known in the art.

The form or mandrel also includes an adjustable support for the box bottom, in order to support the bottom while being fastened to the side walls. Thus, the box bottom support includes a plate 33 of the same shape to correspond with the plates 21 and 22, and having a central shank or stem 34 to fit slidably in the member 10 for the longitudinal adjustment of the bottom support, said shank being clamped in its adjusted position by the set screw 23. The plate 33 has grooves 35 in its outer face in which the extension bars 36 are slidable, said grooves and bars being of dove-tailed cross-section to retain the bars in place, and the outer ends of the bars are preferably provided with heads 37 corresponding in outline with the bars 14. The bars 36 are clamped in their adjusted positions by set screws 38 carried by the plate 33. The bars 36 are flush with the plate 33, for supporting the box bottom.

After the bars 14 have been adjusted according to the size of box to be made, the bars 36 are adjusted accordingly, and the plate 33 is then adjusted to bring the heads 37 adjacent to the corresponding ends of the bars 14. Then, when the side walls of the box are formed on the bars 14, the box bottom can be placed on or against the bottom support and the adjacent edges of the box bottom and walls secured together in the well-known manner.

The form or mandrel can be made in different shapes by having the plates 21 and 22 of various shapes, as shown in Figs. 3, 4 and 5, and the several shapes of forms or mandrels are interchangeable. Thus, by removing the tubular member 10 from the

shaft 11, another form or mandrel can be quickly substituted on said shaft when a box of a different shape is to be made. Each shape of mandrel is adjustable for the production of boxes of different sizes having the corresponding shape, and the forms or mandrels can be used for making practically all shapes of boxes, including square, rectangular, elliptical, circular, triangular and polygonal boxes. It will be noted that in each modification or shape of the form, the side bars are arranged with their outer edges extending outwardly away from the axis of the central supporting member to define the outline of the form, said bars being disposed in radial planes in which the axis of the central supporting member is disposed. This is of advantage instead of using broad outer surfaces for the members defining the outline of the form, because in the different sizes of the form, the outer edges of the side bars will give the paper its proper shape when wrapped around the form, even when circular or elliptical forms are used.

Having thus described the invention, what is claimed as new is:

1. An adjustable box form comprising side bars disposed around the axis of the form and having edges extending outwardly away from said axis to define the outline of the form, and adjustable means supporting said bars for adjustment toward and away from said axis to adjust the form for boxes of different sizes having the same shape.

2. A box form comprising side bars disposed around the axis of the form and having edges extending outwardly away from said axis to define the outline of the form, links supporting said bars, and means for adjusting the links to move said bars toward and away from said axis for adjusting the form for different sizes of boxes having the same shape.

3. A box form comprising side bars disposed around the axis of the form and having edges extending outwardly away from said axis to define the outline of the form, relatively adjustable members at the center of the form, and links connecting said members and bars for adjusting the bars toward and away from said axis by the adjustment of said members, to adjust the form for different sizes of boxes having the same shape.

4. A box form comprising side bars disposed around the axis of the form, members adjustable relatively along the axis of the form, and crossed and pivoted links connecting said members and bars for adjusting the bars toward and away from said axis by the adjustment of said members, some of the links having slidable connections with said bars.

5. A box form comprising a central sup-

porting member, side bars disposed around said member and having edges extending outwardly away from said supporting member to define the outline of the form, and 5 means for adjustably mounting said bars and supporting them from said member for adjustment toward and away from said member to adjust the form for different sizes of boxes having the same shape.

10 6. A box form comprising a central supporting member, side bars disposed around said member parallel therewith, plates on said member of the shape of the boxes to be formed, and links connecting the edge portions of said plates and bars, one of the plates being adjustable on said member for adjusting the bars toward and away from said member.

7. A box form comprising a central supporting member, side bars disposed around said member parallel therewith, plates on said member of the shape of the boxes to be formed, and crossed and pivoted links pivoted to the edge portions of said plates and 25 to the bars, one of the plates being adjustable on said member for adjusting said bars toward and away from said member, and some of the links having slidable connections with said bars.

30 8. An adjustable box form comprising adjustable side members for defining the walls of a box, and a box bottom support adjustable to correspond with the adjustment of said side member.

35 9. An adjustable box form having adjustable side members for defining the walls of a box, and a box bottom support adjustable toward and away from said member axially of the form and having members 40 adjustable according to the adjustment of the side members.

10. An adjustable box form having side members adjustable toward and away from

the axis of the form, and a box bottom support including a plate adjustable along the 45 axis of the form and bars slidably carried by said plate and adjustable toward and away from said axis to correspond with said side members.

11. An adjustable box form comprising a central supporting member, side bars disposed around said member and adjustably connected therewith for adjustment toward and away from said member, and a box bottom support adjustably connected with 55 said member and having portions adjustable toward and away from said axis to be adjusted according to the adjustments of said bars.

12. An adjustable box form comprising 60 a central supporting member, slide bars disposed around said member, means adjustably connecting said member and bars for the adjustment of said bars toward and away from said member, and a box bottom support including a plate having a slideable connection with said member for adjustment axially of the form and bars slidably carried by said plate and adjustable toward 65 and away from said member to be positioned according to the adjustments of said bars.

70 13. An adjustable box form having side members for defining the walls of a box adjustable toward and away from the axis of the form, and a box bottom support having portions adjustable toward and away from said axis to be positioned according to the 75 adjustment of said members.

In testimony whereof I have signed my name to this specification in the presence of two subscribing witnesses.
